UNITED STATES PATENT OFFICE.

JOSEPH B. DE LÉRY, OF NEW YORK, N. Y.

VAPOR-BURNER.

SPECIFICATION forming part of Letters Patent No. 565,471, dated August 11, 1896.

Application filed February 12, 1896. Serial No. 579,007. (No model.)

To all whom it may concern:

Be it known that I, JOSEPH B. DE LÉRY, a citizen of the United States, residing at New York, in the county of New York and State 5 of New York, have invented certain new and useful Improvements in Vapor-Burners, of which the following is a full, clear, and exact description.

This invention relates to burners for that 10 class of lamps in which a volatile hydrocarbon is used as a fuel and in which the heat of the flame is utilized to generate the vapor which is supplied to the burner.

This burner was designed especially to be 15 used upon the lamp described in the application of Hanorah Moran, filed January 25, 1896, Serial No. 576,760; but the invention is not confined to this lamp.

The object of this invention is to provide a 20 combined burner and vapor-generator which shall be simple in construction and efficient in operation.

The invention consists of the construction hereinafter described and claimed.

Referring to the accompanying drawings, 25 Figure 1 represents a side elevation of the lamp. Fig. 2 is a perspective view of the burner, and Fig. 3 is a cross-section of the same.

The lamp proper consists of a reservoir A, 30 which is to contain gasolene or other volatile hydrocarbon. The lamp will have a wick leading from the reservoir through one of the handles a, which will be tubular for that purpose, the wick ending at the upper end of the handle, where the burner is connected.

b represents the burner, the construction of which constitutes the invention herein described. The burner is shown in Figs. 2 and 40 3, wherein it will be seen that it has a ridge b' along its upper edge and a longitudinal groove b² each side of the ridge and a short distance below it. The burner is hollow and provided with a nipple b³ or other means of 45 connection with the upper end of handle a.

In the lower corner of each of the grooves b² a row of perforations is formed, extending into the burner and forming the escape-passages for the vapor. These perforations are

made vertically to direct the vapor as much 50 as possible against the upper edges of the groove, so that when the lamp is burning the ridge b' will become highly heated and the heat will be conducted throughout the entire burner. In the chamber of the burner I place 55 a piece of wire-gauze, (represented by c.) This is in the form of a cylinder and is to distribute the gas or vapor generated in the chamber evenly to the several perforations and to form a kind of cushion for the vapor, preventing 60 it from passing out too freely and tending to keep the flame steady. The groove b² may be located on one or both sides of the ridge; but I prefer to have them on both sides, as 65 shown.

The lamp is lighted by holding a lighted match under the burner for a short time to transform the hydrocarbon contained in the end of the wick adjacent to the burner into a vapor. The vapor soon forces out through 70 the perforations in the groove b² and is then ignited. Therefore the flame itself heats the burner by reason of its contact with the ridge of metal between the grooves. The chamber thus being always hot vaporizes the fuel 75 and automatically supplies a constant flow of gas to the flame.

Having thus described my invention, I claim—

1. A gas or vapor burner provided with a 80 horizontal closed ridge and having sides extending obliquely downward from said ridge, and a groove or grooves located in said oblique sides, through which the gas or vapor flows, substantially as described.

2. A gas or vapor burner provided with a horizontal ridge, a groove parallel to and below the ridge, and a series of perforations for the escape of gas located in the lower corner of said groove, and at right angles thereto, 90 substantially as described.

In testimony whereof I subscribe my signature in presence of two witnesses.

JOSEPH B. DE LÉRY.
